TWIN DRAINAGE FITTING

Filed Oct. 21, 1933

UNITED STATES PATENT OFFICE

1,991,130

TWIN DRAINAGE FITTING

Frederick Anton Warren, Atlanta, Ga.

Application October 21, 1933, Serial No. 694,684

2 Claims. (Cl. 182—31)

Generically this invention relates to drainage devices, but it is more especially directed to a drainage fitting device and method for making and installing same in connection with a drainage system in buildings having inlets at the top and adjacent the bottom of the fitting for effecting drainage of areas above and surrounding said device.

One of the principal objects of this invention is the provision of a twin drainage fitting for a drainage system in buildings comprising inner and outer complementary sections adapted to engage respective surfaces of a flashing sheet formed with an opening registering with the main drainage opening of the fitting and constituting dies to shape the flashing into conformity with the contour of the die faces and means for locking and sealing the sections and flashing into a non-leakable unitary structure whereby seepage below the upper end of the device and above said flashing will be directed into the main drainage opening.

Another important object of this invention is the provision of a drainage fitting comprising complementary inner and outer or upper and lower sections having a cylindrical body section constituting the main drain and a vertical annular flange spaced from said body section forming an annular channel, the bottom of which is formed with a plurality of auxiliary drainage openings, and a removal means telescopically arranged with respect to said body section and engageable with said flange to prevent extraneous matter reaching said channel and clogging said openings during installation of the device.

The present invention relates to an improved twin drainage fitting for drainage systems in buildings and has for its object to provide a device of this character wherein provision is made for a watertight connection between the flashing and the drainage system and especially for draining the seepage from the flashing and the outside of the strainer or body section effected by means of openings in the inner or upper casting fashioned so as to require no cores. The connection between the flashing and the casting is sealed with a low temperature metal or alloy in a molten condition expanded by means of a flat tool to compress the flashing against the outer casting to effect a non-leakable joint.

A further object of this invention is the provision of a twin drainage fitting comprising inner and outer castings uniquely arranged so that the inner casting with openings for strainer and seepage openings may be cast without the aid of cores

and with an inner calking wall designed when operatively placed in the outer casting to form a channel to receive the molten metal which when expanded forms the watertight connection. The said inner calking wall is so designed that a sleeve can be placed in said channel to protect the seepage openings from becoming clogged with cement, concrete, or other substances during installation. Said inner casting also acts as a die in forming the flashing in contour with said castings and permitting it to extend from the floor or roof to the main drain.

With these and other objects in view, which will become more apparent as the description proceeds, the invention resides in the construction, combination and arrangement of parts, herein-after more fully described and claimed, and illustrated in the accompanying drawing, in which like characters of reference indicate like parts throughout the several figures, of which:

Fig. 1 is a vertical cross sectional view through my improved twin drainage fitting illustrating the same in operative position.

Fig. 2 is a top plan view partly in section taken on the line 2—2 of Fig. 1.

Fig. 3 is a vertical sectional view of the upper casting with removable sleeve in operative position.

Heretofore the general custom has been to employ two separate castings supposed to make a watertight connection between the flashing and castings by means of screws, bolts, or clamping devices, which method has proven unsatisfactory for the reason that gravel, cement, and other foreign substances get under the flashing and prevent a face to face connection between the castings and the flashing, also rough castings prevent a watertight connection; the seepage openings being made by drilling small holes in the castings often become clogged and in some cases slots are provided in the strainer base which method causes the drainage water to pass over the cement causing it to become saturated, and in other cases small grooves are provided in the clamping device which likewise become stopped up, thereby defeating their purpose, and it was to overcome such disadvantages and to provide a drainage device comprising a lower or outer substantially funnel-like section having an inclined wall portion terminating at its upper end

in a vertical annular flange adapted to engage the under surface of a flashing sheet, such flashing extending to the main drainage opening, and a complementary section formed with a central tubular body section and an annular vertical

slot.

flange spaced from said central section to form a channel surrounding same, the bottom of said channel being formed with a plurality of drainage openings, the under surface of said upper section being inclined complementally with respect to the lower section and formed with a lateral flange, said section adapted to act as a die in shaping the flashing to conform to the interior contour of said lower section and said lateral flange forming a seat for calking means adapted to effect a watertight joint and interlock said castings and flashing into a unitary structure, so that seepage above said flashing is directed through said device, that I designed the twin drainage fitting forming the subject matter of this invention.

In the illustrated embodiment characterizing this invention there is shown a double or twin drainage fitting device A for floors, roofs, and the like, adapted for connection with the drainage system of a building designated as B.

In the present instance the device A is shown as mounted in and adapted to effect drainage of a floor 1 and comprises the complemental inner casting section 2 and outer casting section 3. The outer section 3 is formed with a central depending internally threaded annular flange 4 and flaring or extending outwardly and upwardly therefrom is the inclined section 5 terminating at its upper end in the vertical wall or hub member 6. Said supporting or outer section 3 is adapted to be threadedly mounted on the upper end of main drain pipe B of the drainage system with central opening 7 of the same diameter as pipe B and registering therewith. Flashing sheet 8 of lead, copper, or any suitable waterproofing material is then placed over outer section 3 and shaped to conform to the contour thereof by inner or die section 2 so that opening 9 of the same diameter or slightly larger than opening 7 will register with the latter.

The inner or die section 2 comprises an annular vertical flange or wall 10 internally threaded as at 11 and is formed adjacent the lower edge of said threads with a lateral flange 12 forming an opening 13 adapted to register with openings 7 and 9 and constituting a stop or seat for the pipe or body section 14 threadedly mounted in said section 2 and adapted to form a continuation of pipe B as will be apparent. The wall 10 extends below flange 12 and is formed with an upwardly and outwardly extending portion 15 constituting the bottom of channel 16 and terminating in a vertical wall or flange 17 spaced from wall 10, one surface of which constitutes the outer wall surface of channel 16 and the other surface the calking wall surface of channel 18 formed by walls 17 and 6. Adjacent its lower end, wall 17 is formed with a lateral flange 19 adapted to contact flashing sheet 8 and shape it to engage the inner surface of wall 6 and lock or hold same in such position as said die section 2 is forced downward and with the under surface of bottom 15 and flange 19 complementally inclined with respect to the inclined seat 5' of section 5, simultaneously shaping and seating said flashing on said surface 5' with the flashing extending below the complemental faces of sections 2 and 3 and adjacent outlet opening 7 in section 3, so that any seepage from above the flashing or any possible leakage through the connection of parts of the device can only escape from opening 7 to drain B. Channel 16 is formed with a plurality of openings 21 through which water or other fluid is directed from said channel to drain pipe B.

The joint or connection between the sections 2 and 3 and the flashing 8 is sealed preferably by filling channel 18 with a low temperature molten metal C such as lead, tin, or alloy, and which is adapted to be worked into cooperative position by 5 a suitable flat tool with respect to the flashing 8, flange seat 19, and wall 10 to effect a watertight joint as will be apparent.

By reason of the above structural arrangement it will be noted that no seepage from above flashing 8 and no leakage between sections 2 and 3 by reason of rough or non-tight fitting complemental faces can escape except through opening 7 and main drain B. Also leakage from the device by reason of the employment of bolts or other 15 clamping devices between the complemental sections is eliminated and the structural arrangement of the device greatly simplified.

Threadedly mounted on the upper end of body section 14 is a substantially funnel-shaped 20 strainer section 22 constituting the top section of the device and formed in the present instance with a slotted face 23 adapted to seat in the countersunk opening 24 formed in the tiles or other suitable floor 25 which said device is 25 adapted to drain.

The device A is shown, in the present instance, as mounted in concrete 26, and during the installation of the device and in order to protect and prevent extraneous matter from clogging 30 openings 21 or the device below said openings during pouring of the concrete above said flashing, a cylindrical member 27 is telescopically arranged with respect to the body of the device with its lower end seating in channel 16 and 35 supported by wall 17, and not only preventing clogging of the device during course of installation, but providing a space 28 surrounding the upper end of the device permitting the expeditious removal of sections 22 and 14 for purposes 40 of cleaning, replacement, etc., as desired.

While the operation and installation of the device would seem to be clear from the above description it might be well to further state that outer section 3 is first mounted on main drain 45 pipe B of the drainage system, then concrete 26 is poured up to the level or slightly above the upper edge of wall 6, then flashing sheet 8 is placed on the concrete and section 3 with opening 9 in registration with opening 7, then inner 50 die section 2 is placed over said sheet and driven or forced down within the outer casting or section 3 shaping the sheet to conform to the contour of said section and locking it therein, then channel 18 is filled with molten metal C which 55 is expanded preferably by means of a flat tool to effect a watertight joint and to unite the sections and flashing into a unitary structure, then sleeve 27 of sufficient length to reach to or above the level of floor or roof 1 is placed in channel 60 16 and concrete 26 is then poured on said flashing and around said sleeve to the desired height or to floor 1. After said concrete has set, sleeve 27 is removed and body section 14 with strainer section 22 is then positioned, after which tile 65 or other floor material 1 is laid, which completes the installation of the device. The device is then suitably mounted to effect drainage of floor 1 through strainer 22 to pipe B and any seepage through concrete 26 above flashing sheet 8 will 70 be directed to channel 16 through openings 21 and to pipe B, as will be clear without further discussion.

In this connection it will be observed that I have provided a drainage fitting comprising twin 75

or complementary inner and outer sections where-
in the inner section is adapted to shape a flash-
ing sheet to conform to the contour of the outer
section, without the use of any shaping tools
5 and the like, the coaction and relation of the
parts being such that even should the calking
material C leak or be omitted the flashing sheet
would be held in position and the device would
still function to direct any leakage or seepage
10 above said flashing into the main drain B.

10 From the above it will be apparent that I have
designed a twin drainage fitting comprising few
parts, expeditiously installable, manufacturable
at a minimum of production cost, and efficient
15 for the purposes intended.

15 Although in practice I have found that the
form of my invention illustrated in the accom-
panying drawing and referred to in the above
description as the preferred embodiment is the
most efficient and practical, yet realizing the
20 conditions concurrent with the adoption of my in-
vention will necessarily vary, I desire to empha-
size that various minor changes in details of
construction, proportion and arrangement of
parts, may be resorted to within the scope of the
25 appended claims without departing from or
sacrificing any of the principles of this invention.

Having thus described my invention, what I
desire protected by Letters Patent is as set forth
30 in the following claims:

30 1. A drainage device for draining a floor, roof,
or like area and an area surrounding said device
below said floor, comprising an outer section

having a well and an inner section engageable
in said outer section and adapted to shape a
flashing sheet to the contour of said outer sec-
tion and maintain the same in engagement
therewith, wall means carried by said inner sec-
tion adapted, when said section is operatively
positioned, to form in conjunction with the wall
5 of the outer section an annular recess, calking
means in said recess for effecting a watertight
connection between said sections and flashing
sheet, and means in connection with said inner
section for directing seepage from the area above
10 said flashing surrounding said device into said
device.

2. A method of constructing a drainage fitting
for house drainage systems consisting in embed-
ding an outer section of the fitting in concrete,
placing a flashing sheet over said concrete and
section, and shaping said sheet to conform with
the contour of the outer section by pressing down
thereon an inner section having main and auxili-
ary openings communicating with said outer
section, then arranging a cylindrical member ex-
teriorly with respect to said inner section, then
pouring concrete surrounding said cylindrical
member and over said flashing, and when said
concrete has set removing the cylindrical mem-
ber, whereby clogging of said auxiliary openings
25 during construction of the device is prevented
and spacing and shaping of the concrete wall
30 with respect to the inner section is effected.

FREDERICK ANTON WARREN.
